(57) **CLAIM**

The ornamental design for a recreational slide, as shown and described.

DESCRIPTION

FIG. 1 is a front left perspective view of the first embodiment of a recreational slide showing my new design;
FIG. 2 is a left side view of the recreational slide of FIG. 1;
FIG. 3 is a right side view thereof;
FIG. 4 is a front view thereof;
FIG. 5 is a rear view thereof;
FIG. 6 is a top view thereof;
FIG. 7 is a bottom view thereof;
FIG. 8 is a front left perspective view of the second embodiment of a recreational slide showing my new design;
FIG. 9 is a left side view of the recreational slide of FIG. 8;
FIG. 10 is a right side view thereof;
FIG. 11 is a front view thereof;
FIG. 12 is a rear view thereof;
FIG. 13 is a top view thereof; and,
FIG. 14 is a bottom view thereof.

The broken lines in the figures depict portions of the article that form no part of the claimed design.

1 Claim, 12 Drawing Sheets
